US0D1093985S

(12) **United States Design Patent** (10) **Patent No.:** **US D1,093,985 S**
(45) **Date of Patent:** **** Sep. 23, 2025**

(54) **CABINET SMOKER**

(71) Applicant: **MILL SCALE LLC**, Lockhart, TX (US)

(72) Inventors: **Matthew James Johnson**, Lockhart, TX (US); **Caleb Leland Johnson**, Lockhart, TX (US)

(73) Assignee: **MILL SCALE LLC**, Lockhart, TX (US)

(**) Term: **15 Years**

(21) Appl. No.: **29/933,938**

(22) Filed: **Mar. 22, 2024**

(51) **LOC (15) Cl.** **07-02**

(52) **U.S. Cl.**

USPC **D7/332; D7/334**

(58) **Field of Classification Search**

USPC D7/323, 332, 333, 334, 335, 336, 337, D7/338, 339, 350.1, 402, 403, 404, 405, D7/406, 407, 408, 409, 99/481

CPC A23B 4/052; A47J 37/07; A47J 37/0704; A47J 37/0763

See application file for complete search history.

(57) **CLAIM**

The ornamental design for a cabinet smoker, as shown and described.

DESCRIPTION

FIG. 1 is a perspective view of a cabinet smoker showing our new design;

FIG. 2 is a front elevation view of the design of FIG. 1; FIG. 3 is a back elevation view of the design of FIG. 1; FIG. 4 is a left-side elevation view of the design of FIG. 1; FIG. 5 is a right-side elevation view of the design of FIG. 1; FIG. 6 is a top view of the design of FIG. 1; and, FIG. 7 is a bottom view of the design of FIG. 1.

1 Claim, 6 Drawing Sheets
